CLAIM

(57) The ornamental design for a food support rack, as shown and described.

DESCRIPTION

FIG. 1 is a perspective view of a food support rack of the present invention;

FIG. 2 is a perspective view of a food support rack of the present invention with the food support elements in a reversed position;

FIG. 3 is a perspective view of a frame of the food support rack of FIGS. 1 and 2;

FIG. 4 is a top plan view of an alternative embodiment of the food support rack of the present invention;

FIG. 5 is a top plan view of an alternative frame of the food support rack of FIG. 4;

FIG. 6 is a right side elevational view of the food support rack of FIG. 4 with the food support elements installed;

FIG. 7 is a left side elevational view of the food support rack of FIG. 6;

FIG. 8 is a front elevational view of the food support rack of FIG. 4 with the food support elements in a reversed position; and,

FIG. 9 is a rear elevational view of the food support rack of FIG. 4.
